UNITED STATES PATENT OFFICE.

JAMES McKECHNIE, OF BARROW-IN-FURNESS, ENGLAND, ASSIGNOR TO VICKERS SONS & MAXIM, LIMITED, OF SHEFFIELD AND LONDON, ENGLAND.

TUBULOUS STEAM-GENERATOR.

SPECIFICATION forming part of Letters Patent No. 740,032, dated September 29, 1903.

Application filed December 24, 1901. Serial No. 87,101. (No model.)

To all whom it may concern:

Be it known that I, JAMES McKECHNIE, a subject of His Majesty the King of Great Britain, residing at Barrow-in-Furness, in the 5 county of Lancaster, England, have invented a certain new and useful Improvement in Tubulous Steam-Generators, of which the following is a specification.

This invention relates to the class of tubulous steam-generators having a number of vertical or inclined water tubes or headers divided by a partition and connected to a steam and water drum, to which headers are connected at approximately right angles a 15 number of steam-generating and water-circulating elements arranged over the furnace, each element consisting of an outer tube closed at one end and open at the other to one side of the header and of an inner tube open 20 at one end to the outer tube and at the other to the other side of the header, the object of my invention being to improve certain details in the arrangement and construction of the headers whereby greater efficiency is obtained.

In the accompanying drawings, Figure 1 is a sectional elevation of a part of a generator, showing my improvement. Fig. 2 is a side elevation, partly in section, of the improved 30 construction and arrangement of a pair of headers. Fig. 3 is a front elevation of such a pair of headers. Fig. 4 is a plan showing the arrangement of the headers in pairs. Fig. 5 is a sectional plan, on a still larger scale, of a header and an element carried thereby.

The generator comprises the usual water and steam drum 1, headers 2, and elements or double tubes 3 connected thereto, as seen in Fig. 1.

For the purpose of economizing space I form 40 the headers as follows: Each consists of a tube, the original outside diameter of which is indicated by the dotted line 4 in Fig. 5, which is subsequently reduced to bring its exterior form to an oval shape, as shown in such figure and also in dotted line, Fig. 4. This gives a thin side and thickened end portions, in which are secured, respectively, the outer tube or steam-generating element 5 and the

50 hand-hole caps 6, the construction of which

does not form part of the present invention. Each two headers 2, forming a pair, are secured in or provided with a flanged head 7, and for the purpose of holding same therein they are preferably again reduced in diameter to the form of a cylindrical tube, the wall of which is of equal thickness throughout, as shown at 8, Figs. 1, 2, and 4, such reduced portion being secured with head 7 by expanding it therein or in any other suitable way. 60 These heads 7 are placed at an angle, as shown in Fig. 4, so that though the headers are in two parallel lines every other one or the second of each pair is behind the first and occupies a space intermediate of that and the 65 first one of the next succeeding pair, with the result that the numbers of points of connection of the headers with the drum 1 is reduced and more can be placed in the same space than if each had a separate flange connection, two rows being easily obtained in place of one, as is usual in this type of generator.

The inner tube or water-circulating element 9 is carried in the header by a partition 10, 75 consisting of a straight plate or plates continuous from one end of the header to the other and held in grooved lugs 11 11, having screw-threaded portions 12, by which they can be screwed into the walls of the header 2 from 80 the outside, the plate 10 passing freely into the grooves of such lugs, so that it can be dropped into position in the header and also be easily withdrawn without affecting the latter.

The plate 10 is preferably carried up into the drum 1 and provided with a curved portion 10^a, which will serve to direct and assist the circulation of water and steam out of the rear compartment of the header and the elements 5, and another curved collecting-plate 14 may be carried inside such drum to direct and assist the circulation into the front compartment and the element 9, if desired.

The tubes 9 are preferably provided with 95 bell-mouthed attachments 13; but this and their manner of connection to the plate 10 do not form part of the present invention.

The construction of the outer tube 5 and the means of supporting the tube 9 therein 100

form the subject of a separate divisional application hereof.

For the purpose of supporting the free ends of the elements 5 in such a manner that they 5 may freely expand and contract I provide a supporting-framework consisting of a number of vertical or approximately vertical bars 15 in pairs, each pair being connected by a rivet inside a tubular ferrule or sleeve 17, 10 forming a ladder-shaped structure on the rungs of which each tube rests.

The group or nest of circulating and generating tubes or elements may be divided into a number of combustion-chambers by portable 15 baffle-plates 21.

What I claim is—

1. In a tubulous steam-generator of the class described, the combination with a steam and water drum of headers arranged in pairs 20 one of each pair being behind the axial line of the other and means for carrying such headers in pairs.
2. In a tubulous steam-generator of the class described the combination with a steam 25 and water drum of a series of flanged heads and a pair of headers carried by each of such

flanged heads one of each pair being behind the axial line of the other.

3. In a tubulous steam-generator of the class described, the combination with a steam 30 and water drum of a pair of headers each of oval exterior section and circular interior section, arranged in pairs, one of each pair being behind the axial line of the other and a flanged head in which each pair of headers is 35 carried.

4. In a tubulous steam-generator of the class described, and in combination, a header, a series of grooved lugs projecting through the walls into the interior of same, means for 40 introducing such lugs from the outside of the header and holding them in the walls and a continuous partition-plate held in the grooves of such lugs.

In testimony whereof I have hereunto set 45 my hand in the presence of two subscribing witnesses.

JAMES MCKECHNIE.
